TUBE CLEANING APPARATUS

Paul T. Keebler and Virgil H. Baker, Springfield, Ohio, assignors to Elliott Company, Pittsburgh, Pa., a corporation of Pennsylvania

Application December 16, 1940; Serial No. 370,280

9 Claims. (Cl. 15—104.14)

This invention pertains to motor driven cutter and cleaner heads suitable for cleaning interior deposits in tubes, such as heavy coke. More particularly, the invention relates to an improved cutter head having roughing and polishing elements in operative combination.

It has been an object of our invention to provide a new and improved cutter unit of a type that will be particularly suitable for removing coke and other extraneous material where the taper of the cut surface is significant.

Another object has been to provide a cutter unit having improved characteristics of flexibility.

A further object has been to devise a cleaner head combination having at least two types of cleaner or cutter elements in operative combination such that the elements of one type can best effect desired operative results without undesirable modification by the other type of elements.

These and many other objects of our invention will appear to those skilled in the art from the description, the drawings, and the appended claims.

In the drawings:

Figure 1 is a side elevation, partly in section, showing one form of our invention;

Figure 2 is a side sectional elevation showing cutter elements and pins of Figure 1;

Figure 3 is an end sectional view in elevation taken along the line III—III of Figure 1;

Figure 4 is an exploded side sectional elevation showing a modified arrangement of cutter elements and pins;

Figure 5 is a side elevation showing in detail the spider construction of Figure 1;

Figure 6 is a plan view of the front end (left of Figure 5) of the spider of Figure 5, and Figure 7 is a similar view of the rear end (right of Figure 5);

Figure 8 is a side elevation, and Figure 9 is a plan view of a front plate detail of the embodiment of Figure 1;

Figure 10 is an end plan view in elevation, partially in section, of a detail of a rear plate of the embodiment of Figure 1; and

Figure 11 is a vertical section taken along the line XI—XI of Figure 10.

Heretofore in present-day commercial constructions, it has been customary to mount a number of cutter or cleaner elements on the same journal pin arrangement. We have found that this construction has certain disadvan-

tageous results, particularly as applied to tubing having heavy coke encrustations therein. In such a construction, the forward cutter elements are generally tapered and the other elements of the rear are of substantially cylindrical form.

We have determined that the preferable type of operation is for the forward or conical cutters to advance at a suitable inclination with respect to the axis of the unit (to effect self-feed); and at a suitable inclination into the coke encrustation without setting up an undesired inclination and positioning of the rear or finishing cutters. To effect a uniform job, the finishing cutters should preferably move somewhat

15 parallel to the axis of the body being cleaned, and thus, be capable of somewhat parallel positioning with respect to the rotating cutter head or spindle. To effect such a result, it will be apparent that a suitable flexibility or adaptability is needed between the two types of cutter elements and that this cannot be accomplished by the utilization of a single common supporting journal pin or by other arrangements familiar to those skilled in the art.

20 Particularly as applied to a self-feeding type of cutter head, see for example, the arrangements shown in the Keebler Patent 2,138,009, it is desirable to operate one set of cutters, the leading, cone, or roughing cutters, in such a manner that their operating axes are at an angle to the operating or rotating axis of the head. During the operation of the unit, the cleaning cutters should be preferably mounted in such a manner that they can move to a position in which their axes are parallel to the axis of the head as well as at an angle thereto.

25 In a preferred form of our invention of Figure 1, we have shown a spider 10 having a front head portion 11, three or any suitable number of longitudinally and backwardly extending integral arm portions 12, and a back or rear head portion 13. A front plate element 15 is provided with outwardly-extending ears 16 which, as shown in Figures 1, 8, and 9, fit between the integral arms 12 and abut against an inner side of the front head portion 11. The plate 15 is removably positioned and each of its ears 16 is provided with a bearing hole or slot 17 for receiving and journaling a cutter pin. The slots or recesses 17 may be circular or radially elongated, as shown in Figures 7 and 8 of the above-mentioned Keebler patent.

30 Front cutter or journal pins 18 are removably mounted at one end in each of the slots 17 to longitudinally extend backwardly therefrom and

support forward, cone-shaped cutter elements or heads 20. Cutter teeth portions 21 of the elements 20 are of integral form and are spaced by annularly-extending grooves 22. The rear portion of each forward cutter element 20 is provided with a longitudinally-extending bore or opening therein that is radially offset from an opening or bore in the front portion thereof and is suitable for receiving a second or rear cutter pin 25. The rear cutter pin 25 is preferably at least as strong or of as great a diameter as the forward cutter pin 18 and is preferably of greater diameter.

The rear cutter or journal pins 25 are at one end journaled substantially loosely within and extend from the portions 23 of the cutter elements 20. Suitable clearance may be allowed between the ends of the pins 18 and 25 to provide a suitable pivot action between the forward ends of the pins 25 and the female wall portions 23 of the forward cutters 20; both ends of these female portions or bores are preferably chamfered. In this manner, the cutters 20 are, in effect, supported on two cutter pins. A pair of straight, cylindrical, finishing, or rear cutter elements 30 are operably mounted beyond and adjacent as well as in substantial abutment with the forward cutter element 20 upon an extending portion of each second or rear cutter pin 25. In this manner, the forward pin 18 is held in operative position by the pin 25 and the latter takes up thrust upon the forward pin 18, transferring it through its length to a rear head lock plate or member 32.

As shown particularly in Figures 1, 2, and 4, the pin 25 is preferably provided at its rear end with an annular thrust flange 26 and a somewhat beveled stud end portion 27 that is loosely and somewhat pivotally journaled within slotted portions 33 of the rear head lock plate 32. Small openings 34 are provided in the top of these slotted journal portions 33; openings 35 are also provided in body portions of the plate 32 for passage of fluids.

The entire arrangement is demountable in such a manner that the wearing parts can be readily replaced. As shown particularly in Figures 1, 10, and 11, the rear plate 32 has a series of undercut offset portions 36 for receiving the arms 12 of the spider. The plate 32 is removably mounted on the frame or spider 10; a connector 40 abuts rear plate 32 and is threaded within a female portion 41 of the spider 10 to secure the rear plate in position. In a mounted position, a center annulus 37 in the rear plate 32 fits over flange 14 of the spider 10, also offset portions 36 fit over portions 13 of the spider. The threads are preferably such that they will be tightened during the rotation of the cutter head.

In view of the above description, it will be apparent that the arrangement can be readily dismounted by unscrewing the connector 40, lifting the rear head plate 32 away from the rear portions of the spider 10, and then pulling the pins 25 and finally the pins 18 backwardly out of their operative positions.

The above arrangement, as will be apparent, makes possible a closely associated mounting of the two types of cutter elements while permitting them to operate in the most efficient manner to effect their cooperative results. That is, the front cutter elements 20 can pivot to a suitable feeding and rough-cutting relationship with the inside of the pipe and the coke to be removed, while the finishing cutter elements 30 are inde-

pendently and adjustably mounted or pivoted with respect to the elements 20 to best complete the cutting and cleaning operation without setting up offsetting and undesired results in combination. The cutters 30 are, in effect, pivoted on the cutters 20; we provide suitable play or clearance between cutters to permit their axial movement on the pins.

By providing a removable front plate, movable journal or cutter pins, and a removable rear plate, the parts subjected to the most wear can be readily and inexpensively replaced. The front cutter pins are operably held in position and strengthened against thrust by the rear cutter pins 25 which are in substantial axial alignment and are at least preferably in a substantial end-to-end relationship. Suitable clearance is provided to permit desired relative movement between pins. The unit will readily adapt itself to any type of heavily coked tube surface. By eliminating a single pin for cutters of different types, we also eliminate bending fatigue and thereby increase the life of the unit. There is no cramping of the operation of the cutters of one type by the operation of the cutters of the other type, in that each has an axially-adjustable or pivotal operating relationship with respect to the other.

It will also be noted that the front cutter element 20, in effect, constitutes a continuation of the cutter pins, in that both of them are operably supported therein. They, in turn, operably and adjustably support the front cutter element. The front cutter element, in effect, pivotally supports the rear cutter pin 25 upon which the rear, cylindrical, or straight cutter elements 30 are operably mounted.

In Figure 4, we have shown a modified form of our invention in which a forward cutting element 20' is combined as a single integral element with the forward pin 18'. We prefer the arrangement shown in Figure 1 in that the wearing parts can be replaced with minimum expense.

It will appear that the core axis of the cutter 45 20', in effect, constitutes an integral portion of the pin 18' such that this pin is mounted in an endwise relationship with respect to the pin 25, a relationship that corresponds to the relationship between the pins 18 and 25 of the embodiment of Figure 2.

It will be apparent to those skilled in the art, although we have shown forms of our invention to illustrate its principles and novel features, that the inventive concept is not limited thereto. 55 That is, the particular cutter construction of the spindles, etc., can be suitably modified and other arrangements of cutters may be employed to utilize our new and improved form of flexible mounting between cutter element types. Also, 60 various arrangements may be employed to utilize our ideas of support and journal construction for the cutter pins.

We claim:

1. In a rotary tube cleaner head having a support frame provided with bearing portions, a cutter having a longitudinal operating axis, a cutter pin operably mounting said cutter adjacent one end thereof in one bearing portion of the support frame, said cutter having a longitudinally-extending bore portion open to an opposite end thereof, the bearing portion of the support frame adjacent the last-mentioned end of said cutter having an outwardly-extending slot, a second cutter pin having a portion of substantially uniform diameter therealong operably and loosely

mounted within said bore portion and extending outwardly therefrom to operably mount the opposite end of said cutter within the slotted bearing portion, so that the longitudinal operating axis of said cutter will move in an angular relation to a longitudinal axis of the cleaner head.

2. In a rotary tube cleaner head having a support frame with spaced-apart pin-mounting portions, a pair of cutter pins operably mounted in said pin-mounting portions of the support frame and extending longitudinally therefrom towards each other in a substantially end-to-end relationship, and a cutter operably mounting the end-to-end portions of said cutter pins with respect to each other in such a manner that one of said pins will move into endwise abutment with the other of said pins under thrust conditions, the other of said pins having a thrust shoulder portion.

3. In a rotary tube cleaner head having a support frame, a pair of cutters, each of said cutters having a longitudinal operating axis, a cutter pin operably mounting one of said cutters adjacent an end thereof on the support frame, a second cutter pin operably extending from said first-mentioned cutter adjacent an opposite end thereof and operably mounting said cutter on the support frame, the second cutter of said pair being operably mounted on said second cutter pin between said first-mentioned cutter and the support frame, at least one of said cutter pins and said first-mentioned cutter being loosely mounted to provide angular movement between the axes of said cutters during a tube cleaning operation, so that the longitudinal axis of one of said cutters will move in an angular relation to the longitudinal axis of the other of said cutters.

4. In a rotary tube cleaner head having a support frame, a pair of cutters, each of said cutters having a longitudinal operating axis, a cutter pin operably mounting one of said cutters adjacent an end thereof in the support frame, a second cutter pin extending into an opposite end of said first-mentioned cutter and operably mounting the other cutter of said pair between said first-mentioned cutter and the support frame, said cutters and cutter pins being mounted in such a manner as to allow one of said cutters to move in an angular relation to the axes of the other of said cutters during a rotation of said cleaner head.

5. In a rotary tube cleaner head having a support frame provided with bearing portions, a pair of cutters, each of said cutters having a longitudinal operating axis, cutter pins extending from opposite end portions of one of said cutters and mounting said cutter in the bearing portions of said support frame, at least one of said bearing portions having an outwardly-extending bearing slot, said bearing portions having portions for limiting the extent of outward movement of said cutter pins, the other cutter of said pair being operably mounted on one of said cutter pins between said first-mentioned cutter and the support frame, said first-mentioned cutter and said cutter pins having portions so mounted that one of said cutters is free to move angularly with respect to the other of said cutters during a tube cleaning operation in such a manner that the longitudinal axis of one of said cutters can move in

an angular relation to the axis of the other of said cutters.

6. In a rotary tube cleaner head having a support frame, at least a pair of cutters, each of said cutters having a longitudinal operating axis, a pair of cutter pins extending from opposite ends of one of said cutters and mounting said cutter on the support frame, one of said cutter pins being loosely associated with said first-mentioned cutter and having the other of said cutters operably mounted thereon so that the longitudinal axis of one of said cutters will move in an angular relation to the axis of the other of said cutters.

7. In a rotary tube cleaner head having a support frame provided with bearing portions, a pair of cutters, each of said cutters having a longitudinal operating axis, cutter pins operably mounting one of said cutters adjacent opposite ends thereof in the bearing portions of the support frame, one of said cutter pins being loosely mounted between said first-mentioned cutter and one of the bearing portions, the other of said pair of cutters being operably mounted on said loosely mounted cutter pin in such a manner that said second-mentioned cutter will be free to change the relation of its longitudinal axis with respect to the longitudinal axis of the first-mentioned cutter to provide angular movement between the longitudinal axes of said cutters.

8. In a rotary tube cleaner head having a support frame, a longitudinally-extending cutter having connected bore portions open to opposite longitudinal ends thereof, the bore portion at one end of said cutter having a smaller diameter than the bore portion at the other end thereof, a cutter pin operably and turnably mounted within the bore portion of smaller diameter and extending therefrom to cooperate with the support frame, a second cutter pin of greater diameter operably and turnably mounted in the bore portion of greater diameter and extending therefrom to cooperate with the support frame, a second cutter operably mounted on said pin of greater diameter, one of said cutter pins having a portion providing a mounted relationship with said first-mentioned cutter such as to allow relative angular movement of axes of said two cutters.

9. In a rotary tube cleaner head having a support frame with spaced-apart pin-mounting portions, a cutter pin operably mounted in one of said pin-mounting portions of the support frame and extending longitudinally therefrom, a cutter operably positioned on said cutter pin between said pin-mounting portions of the support frame, said cutter having an integral pin extending from an end thereof and operably mounted in the other of said pin-mounting portions of the support frame, said cutter element operably mounting an extending end portion of said first-mentioned cutter pin in a substantially endwise relationship with respect to a portion integral with said second-mentioned pin in such a manner that said first-mentioned pin will move into endwise abutment with the integral portion of the other of said pins under thrust conditions, said first-mentioned pin having a thrust shoulder portion.

PAUL T. KEEBLER.
